UNITED STATES PATENT OFFICE.

ALVAH G. LINEBACK, OF FALLS CITY, OREGON, ASSIGNOR OF ONE-FOURTH TO JAMES R. CHAMBERS, ONE-FOURTH TO IDA DAVENPORT, AND ONE-FOURTH TO SARAH LINEBACK, ALL OF ALBANY, OREGON.

ARM-REST FOR CRUTCHES.

1,232,057.

Specification of Letters Patent.

Patented July 3, 1917.

Application filed December 1, 1915. Serial No. 64,516.

To all whom it may concern:

Be it known that I, ALVAH G. LINEBACK, citizen of the United States of America, residing at Falls City, in the county of Polk and State of Oregon, have invented certain new and useful Improvements in Arm-Rests for Crutches; and I do hereby declare the following to be a full, clear, and exact description of the invention, such as will enable others skilled in the art to which it appertains to make and use the same.

This invention relates to crutches and has for its object to provide an efficient and durable cushion for the head or arm rest of a crutch.

Another object is the provision of a cushion or the head of a crutch of hollow elastic formation adapted to be inflated with air to increase the resiliency and efficiency thereof.

Another object is the provision of a pneumatic cushion for the heads of crutches and novel and efficient means for reliably securing the cushion in position upon the head.

With these and other objects in view, the invention consists in the novel construction, arrangement and formation of parts as will be hereinafter specifically described, claimed and illustrated in the accompanying drawing, in which:

Figure 1 represents a side elevation, partly broken away and partly in section, of the head portion of a crutch constructed in accordance with this invention.

Fig. 2 represents a transverse sectional view on the line 2—2 of Fig. 1, and

Fig. 3 represents a fragmental sectional view through one end of the crutch head and cushion, illustrating a slightly modified form of the latter.

Referring to the drawing in detail, wherein similar reference numerals designate corresponding parts throughout the several views, the numeral 5 indicates the head of a crutch, which, as usual, is curved from end to end and is secured to the upper extremities of the uprights or standards 6. The upper or concave face of the head 5 is formed with a longitudinal groove 7 in which is seated the cushion designated generally by the numeral 8 and preferably formed of rubber or other similar elastic material. As illustrated in Fig. 2, the body of

the cushion 8 is of tubular formation which is seated in the groove 7 in the head 5 and is preferably formed with closed ends 9 of increased thickness and having integral enlargements or flanges 10 at the extremities thereof.

The central portion of the body of the cushion 8 is formed with an aperture registering with an aperture 11 formed centrally and transversely through the head 5 in which is mounted a hollow valve casing 12 having a head 13 at one end arranged within the body of the cushion to clamp the latter in the groove 7 when the nut 14 is advanced upon the external threads of the casing 12 against the lower recessed face of the head 5. A suitable cement or adhesive is preferably applied between the groove 7 and the lower portion of the cushion 8 to secure the latter in position on the head 5, and the medial portion of the cushion is reliably secured in position by the valve casing 12, head 13 and nut 14. A suitable spring actuated check valve, similar to those used in connection with pneumatic tires, is arranged in the valve casing 12 to prevent the escape of air from the hollow body of the cushion 8 as the latter is being inflated, and a cap 15 is removably fitted upon the lower extremity of the valve casing 12 to prevent admission of dirt and the like to the interior thereof.

A pair of clamps 16 are positioned over the closed ends 9 of the cushion and also encircle the extremities of the head 5. The clamps 16 are preferably formed of metallic straps having the free ends 17 apertured to receive a bolt 18 on the threaded extremity 90 of which is fitted a nut 19, whereby the straps 16 may be drawn tightly to secure the ends of the cushion 8 to the ends of the head 5. As illustrated in Fig. 1 the clamps 16 are arranged slightly inwardly of the annular enlargements 10 on the body of the cushion 8, and said enlargements constitute abutments for engagement with the clamps 16 to prevent inward movement of the apertured extremities of the cushion relative to the head 5.

Referring to the modification of the invention illustrated in Fig. 3 the body 8^a of the cushion is of hollow tubular forma-

tion formed with open ends in which are cemented or otherwise secured plugs 20 preferably formed of rubber. The plugs 20 extend a distance inwardly of the tubular body 8^a and the clamps 16^a are engaged around the body 8^a at a point where the pressure exerted thereby will be received upon the plugs 20. Reinforcing bands 21 are secured around the extremities of the tubular body 8^a outwardly of the clamps 16^a for strengthening and reinforcing the cushion.

From the foregoing, it is apparent that I have provided an efficient and inexpensive pneumatic cushion for crutches which will be extremely comfortable in use and prevent irritation and soreness of the portion of the arm and body of the user which comes in contact therewith. It is also evident that the hollow body 8 may be inflated from time to time by attaching a tire or other pump to the hollow valve casing 12.

What I claim is:

In combination, a crutch including a head having a longitudinal groove in the upper surface thereof, an inflatable cushion positioned in said groove formed of elastic material and having the material forming the end walls increased in thickness to provide solid reinforced ends, flexible clamping straps positioned about the solid ends of said cushion and the ends of said head, means for drawing the ends of each strap together to clamp the cushion in position upon the head, and a check valve connected with said cushion.

In testimony whereof I affix my signature in presence of two witnesses.

ALVAH G. LINEBACK.
